WARING COMPANY, OF PHILADELPHIA, PENNSYLVANIA, A CORPORATION OF
PENNSYLVANIA.

COMBINED FEED-WATER HEATER AND WEIR-METER.

1,159,148.

Specification of Letters Patent.

Patented Nov. 2, 1915.

Application filed August 7, 1911. Serial No. 642,753.

To all whom it may concern:

Be it known that I, DAVID R. YARNALL, a citizen of the United States, residing at Philadelphia, county of Philadelphia, State 5 of Pennsylvania, have invented a new and useful Combined Feed-Water Heater and Weir-Meter, of which the following is a specification.

The main purpose of my invention is the 10 combination of a weir fluid measuring apparatus with a feed water heater, preferably, but not necessarily, of open type, and, most desirably, without interference with the structure or effective operation of the 15 heater.

A further purpose of my invention is to maintain the same pressure and temperature 20 conditions in the notch tank as in the heater, in order that any back pressure found desirable in the heater to accommodate feed water temperatures above normal vaporization may not be disturbed by, nor interfere with the measuring mechanism, and that the pump may receive the feed water at substantially the same excess pressure notwithstanding the intermediate weir measurement.

A further purpose of my invention is to 30 insert a weir measuring mechanism, under back pressure or not as desired, between a pump and a feed water heater, preferably using it as an equalization pool and in combination with checking mechanism against excessive filling of the notch tank.

A further purpose of my invention is to 35 control the quantity of feed water heater gravity discharge in proportion to the rate of pump withdrawal of such water from a weir meter catch basin.

I have preferred to illustrate my invention 40 by one form thereof which has proved practical, inexpensive and efficient, while recognizing that the principles involved might appear in various other physical embodiments. I have illustrated the tank for the weir meter as separate from the water heater instead of built into the heater chiefly because of my desire to apply it to existing heaters as well as new ones without necessity for change in the heater.

Figure 1 is a vertical longitudinal section, partly in elevation, of the preferred embodiment of my invention. Fig. 2 is a section,

looking in the direction of the arrows, taken upon the line 2-2 of Fig. 1. Fig. 3 is a 55 broken section, taken in the direction of the arrows, upon line 3-3 of Fig. 1.

In the drawings, similar numerals refer to like parts.

In my illustration of the feed water heater 60 herein I have selected a standard type and shall explain it sufficiently to point out the location of the general parts but without claim to having invented anything in the heater *per se* and recognizing that my invention is applicable to many, if not all of the forms of feed water heater upon the market.

In the feed water heater selected, 4 is the 65 body of the heater within which are shown cleaning access doors 5, 6 and 7. Steam, ordinarily exhaust, is supplied through the pipe 8 and excess water is removed from it by the separator 9. The make-up water is supplied through pipe 10, in which a valve 70 11 is controlled by means of levers 12, 13, and link 14, so as to control the water inlet by the height of the water within the heater, through float or other means as desired. The heater is further protected against 75 flooding by overflow 15 to any suitable receptacle, not shown. A vacuum breaking device, which may be employed if desired, is 80 indicated at 16.

The heater is provided with a so-called 85 free or atmospheric exhaust 17 which, however, as is well known, is frequently weighted to permit or provide for pressure within the heater corresponding to the maximum temperature of feed water which the heater is 90 intended to deliver. So far, as hereinbefore described, the heater differs in no particulars from existing heaters and the structure indicated need not be changed in any way for the accommodation of my invention.

The hot water outlet pipe 18 is in the same 95 location as is usual for this pipe but instead of being connected directly to the discharge pump 19, as is normally the case, this pipe enters at any point 20 into tank 21. This 100 tank is fluid tight and is preferably connected with the heater in such a way as to maintain the same pressures in both so as not to lose the advantages of any temperatures above that of normal vaporization 105 which may be attained within the heater.

I maintain the pressure equal in the heater and tank by means of a connecting pipe 22, which enters the heater at any suitable point above its overflow and is connected with the tank at a point where it will least disturb the weir flow, being preferably separated from the weir by a baffle plate as will hereinafter more fully appear.

I have preferred to place the valve 23 directly above the float 24 which presses the valve against its seat 25 to shut off water flow from the heater when the water level 26 of the catch-basin 27 attains its predetermined height. Because of this convenience of mechanical connections I have selected the point 20 at the catch-basin end of the tank 21, and far enough remote from the weir therein to avoid undue fluctuation of the float by reason of the water flow. The stem 28, connecting the float and valve, is guided in any suitable bushing 29. Within the tank 21 I provide the weir meter to whose catch-basin reference has already been made. Within this meter I place the partition 30 carrying weir 31, baffle plate 32, float casing 33, incasing float chamber 34, float 35 and other elements hereinafter set out. The purpose of the baffle plate 32 is to protect the body of water 36, between it and weir, from undue disturbances, from water inlet pressure and variation of gaseous flow through the pipe 22, so that the weir shall measure the actual flow as accurately as possible. In furtherance of this purpose the inlet water from the pipe 18 is led by means of pipe 37 to a discharge point at 38 upon the other side of the baffle plate from the weir. The pressure equalizing pipe 22 is also inserted beyond this baffle plate. For convenience in setting the recorder at its zero point I have provided a zero pointer 39 capable of adjustment within bracket 40, here shown as mounted upon baffle plate 32 so that the pointer may be set at the exact height of the weir bottom. I also provide an inspection opening closed by plate 41 so that the recorder may be set at the zero point when the later level is accurately adjusted to zero by assistance of this pointer. In order to keep the water within the float chamber 34 as free from fluctuation as possible I admit water thereto from the main body 36 by means of a pipe 42 having screened outlet 43 and controlled by valve 44. This particular arrangement of parts may be varied and my invention distinctly contemplates the use of other float actuated weir meters in the relations described and claimed herein. This specific illustration is made in response to the requirements that I illustrate and describe the best form known to me of practising my invention. For the same reason I have shown the float connected with the form of recorder illustrated though I recognize that it would be useful

also in connection with any other satisfactory recorder calibrated in agreement with the weir construction used.

The recorder illustrated is boxed at 45 and is bushed at 46 to permit the requisite free movement of stem 47 connected with the float. The stem 47 is extended at 48 below the float to provide for adjustable counterweight 49, preferably in the form of disks retained by the nut 50, so that the float 35 may be immersed to its point of most sensitive flotation. At its upper end the stem 47 is connected with a rack 51 rotating a gear 52 and spiral actuating cylinder 53 by which an arm 54 carrying recording pen 55 is moved over the chart surface of drum 56 to indicate quantities in ordinates and time as abscissæ in the usual manner, and pointer 57 indicates the height roughly on scale 58. The recording chart is placed upon a properly actuated drum 56.

In operation, the hot water heater is operated without modification. The equalizing pipe 22 maintains the same pressure and, hence, temperature conditions in the tank as exist in the heater. The flow of water from the heater to the tank, through the pipes 18—37, is therefore that due to the difference in heads alone and the flow continues without interruption so long as there is water above this level in the hot water heater and the pump 19 carries off the overflow from the weir freely. The catch-basin head above the pump should be sufficient to prevent objectionable vaporization of water in the pump suction.

So long as the water continues to flow from the heater and be carried off by the pump the recorder measures the weir flow. As soon as the pump stops for any reason so that the catch-basin level reaches the predetermined closing level the float 24 closes the valve 23 against its seat 25. This action is, however, not sudden. The level of float for the closure should be sufficiently low to permit outflow of all of the water in the main tank above the lowest notch level without flooding; and this subsequent flow will be properly measured. The float will then reach its zero point and water measurement will stop. It will be seen that while the shut-off of water flow from the heater is not necessarily coincident with the stoppage of the pump as would be the case with the existing direct connection between the pump and the heater they are directly dependent, the one upon the other differing only in time and rapidity of action.

The indirect character of the control of hot water withdrawal by pump action is of advantage in several ways. It acts as a damper between the pump and the feed water heater, relieving the heater from the suddenness of stoppage of flow which might otherwise occur with sudden stoppage of the

pump. It renders the flow continuous instead of intermittent, in the case of an intermittent pump, affording a pool between. This provides a constant supply of water 5 upon the restarting of the pump as distinguished from the uncertain quantity of water in the feed water heater where this pool is not interposed. Furthermore, the reservoir of water in the catch-basin is both 10 larger than and additional to the reservoir of water normally available in the water heater.

It will be seen that my invention equalizes the pressure in a feed water heater and in 15 a fluid-tight tank receiving the discharge therefrom, in order that the discharge flow may be due to gravity alone and the heater pressure may be maintained; and that it measures the water passing therebetween by 20 recording or integrating weir methods, withdrawing the water from the weir catch-basin by a pump under no less favorable conditions than those under which the pump would ordinarily withdraw water from the 25 heater itself while gaining the advantage of the intermediate pool and protecting the weir mechanism against flooding.

What I claim as new and desire to protect by Letters Patent is—

30 1. In a device of the character stated, an open feed water heater having a water storage reservoir in the lower part thereof, a fluid-tight tank connected therewith, a valve in the connection, a pressure connection between the tank and the heater above the water reservoir of the heater, a weir meter chamber and catch basin within the tank, a float in the catch basin and connections between the float and valve controlling the 40 flow of water from the heater reservoir into the tank.

2. In a device of the character stated, a closed meter casing including a weir chamber and a catch basin, a source of irregular 45 supply of water to the weir chamber, an equalizing pressure connection between the weir chamber and the source of supply, an outlet for the catch basin, the water in the catch basin forming a pool between the weir 50 chamber and the outlet, a valve directly controlling inlet of supply water to the weir chamber and means controlled by variations in the level of said pool for regulating the valve to vary flow of the supply water to 55 the weir chamber in proportion to the height of water in the pool thus formed.

3. In a device of the character stated, a weir meter comprising a fluid-tight tank having a receiving chamber and a catch basin, a compartment forming the main 60 source of supply of water for the meter receiving chamber, a gravity water connection between the compartment and the receiving chamber of the meter, a pressure equalizing connection between the compartment and 65 the meter, the catch basin of the meter having an outlet, a valve controlling the flow of water in the gravity water connection, a float in the catch basin of the meter and connections between the float and valve to directly control the quantity of water admitted to the receiving chamber of the meter by the height of water in the meter catch basin.

4. In a device of the character stated, a 75 feed water heater, a fluid-tight tank containing a weir chamber and a catch basin, a water flow connection between the heater and the weir chamber, a valve in the water flow connection, a float in the catch basin, 80 connections between the valve and float controlling the flow of water from the heater into the tank and a second connection between the heater and the tank entering the heater above the water level therein. 85

5. In a device of the character stated, a feed water heater adapted to contain a pool of water in the bottom thereof to act as a reservoir, a steam inlet for the heater, a weir meter comprising a weir chamber and a 90 catch basin, a water connection between the reservoir in the bottom of the heater and the weir chamber, a valve in the water connection, a float in the catch basin, connections between the valve and float closing the 95 valve as water rises in the catch basin and an outlet for the catch basin.

6. In a device of the character stated, a feed water heater having a reservoir in the bottom thereof, a weir meter having a weir 100 chamber and catch basin reservoir therein, an outlet for the catch basin, a gravity water connection between the heater reservoir and weir chamber, a valve in the connection and a float in the catch basin reservoir connected with the valve to open the valve and draw open the heater reservoir as the catch basin reservoir water level is lowered. 105
